US00D854546S

(12) **United States Design Patent** (10) **Patent No.:** **US D854,546 S**
(45) **Date of Patent:** **** Jul. 23, 2019**

(54) **DEVICE COVER**

(71) Applicant: **Amazon Technologies, Inc.**, Seattle, WA (US)

(72) Inventor: **Monica Liane Mecchella**, San Francisco, CA (US)

(73) Assignee: **Amazon Technologies, Inc.**, Seattle, WA (US)

(**) Term: **15 Years**

(21) Appl. No.: **29/641,708**

(22) Filed: **Mar. 23, 2018**

(51) LOC (11) Cl. **14-02**

(52) U.S. Cl.

USPC **D14/440**

(58) **Field of Classification Search**

USPC D14/440; 206/45.23, 320, 45.2; 361/679.55; 294/25; 224/218

CPC ... G06F 1/1628; G06F 1/1626; A47B 23/044; H04B 1/3888; H05K 5/0217

OTHER PUBLICATIONS

Indian Office Action dated Sep. 27, 2018, for the Indian Patent Application No. 310097, a counterpart foreign patent application of the U.S. Appl. No. 9/641,708, 2 pages.

Primary Examiner — Cynthia R Underwood

(74) Attorney, Agent, or Firm — Lee & Hayes, P.C.

(57) **CLAIM**

The ornamental design for a device cover, as shown and described.

DESCRIPTION

FIG. 1 is a front perspective view of a first embodiment of a device cover;

FIG. 2 is a bottom view thereof;

FIG. 3 is a top view thereof;

FIG. 4 is a left-side view thereof;

FIG. 5 is a right-side view thereof;

FIG. 6 is a front view thereof;

FIG. 7 is a back view thereof;

FIG. 8 is a front perspective view of a second embodiment of a device cover;

FIG. 9 is a bottom view thereof;

FIG. 10 is a top view thereof;

FIG. 11 is a left-side view thereof;

FIG. 12 is a right-side view thereof;

FIG. 13 is a front view thereof; and,

FIG. 14 is a back view thereof.

The dashed broken lines depict portions of the device cover that form no part of the claimed design.

1 Claim, 14 Drawing Sheets
